UNITED STATES PATENT OFFICE.

LOUIS CLARENBACH, OF PASSAIC, NEW JERSEY.

TEXTILE-FABRIC-TREATING MACHINE

1,389,627.

Specification of Letters Patent. Patented Sept. 6, 1921.

Application filed November 18, 1920. Serial No. 424,929.

To all whom it may concern:

Be it known that I, LOUIS CLARENBACH, a citizen of the United States, and a resident of Passaic, in the county of Passaic and State of New Jersey, have invented a new and improved Textile-Fabric-Treating Machine, of which the following is a full, clear, and exact description.

This invention relates to machines for treating in liquids textile fabrics in open width or in the form of strings or ropes and has for one of its objects to provide a construction wherein dyeing, scouring, impregnating and otherwise treating of the fabric may be carried on rapidly and uniformly.

Another object of the invention is to provide a machine for treating in liquid either fabrics or yarns in such manner as to cause the treating liquid to quickly and evenly penetrate the cloth or yarns.

A still further object is to provide a machine in which the material being treated will be moved in a substantially horizontal direction forcibly against the treating liquid whereby the time treatment is shortened and uniform results secured.

In the accompanying drawings—

Figure 1 is a longitudinal vertical section from a machine for treating textile fabrics and chain warps, the same disclosing one embodiment of the invention.

Fig. 2 is a transverse section through Fig. 1 on line 2—2.

Fig. 3 is a sectional view through Fig. 1 on line 3—3.

Fig. 4 is a top plan view of the construction shown in Fig. 1.

In using the machine the treatment of the cloth may be washing, dyeing, impregnating with the washing or other compound or for treating the fabric or yarns for other purposes. The fabric may be passed through the machine either in the form of ropes or strings or in open width, the open width being preferable in the case of cloth, whereas as in the case of yarns the slightly twisted strings of rope form and are acted upon in a positive and forceful manner as they pass.

In treating the fabric according to the present invention, one or a large number of tanks could be used according to the amount of treatment desired and other circumstances surrounding the particular material being treated. In the accompanying drawings, only two tanks 1 and 2 have been shown,

From Fig. 1 it will be seen that the tank 1 is provided with a quantity of liquid which may be dye, scouring liquid or other treating liquid. Adjacent the bottom of tank 1 is arranged a series of coils 10 which may be supplied with steam or other heating means to maintain the treating solution at the desired temperature. Arranged adjacent the top and the bottom of tank 1 are guiding rollers 11 which guide the respective bars 12 and 12' as they reciprocate. These bars extend through suitable packing boxes 13 and 14 and are connected to the respective connecting rods 15 and 16 which connecting rods are connected with the respective crank shafts 17 and 18. Similar connecting rods and other parts are provided in respect to the tank 2 but as the parts are identical, no additional description is necessary. The shaft 18 has a gear wheel 19 rigidly secured thereto which continually meshes with an idler 20 and said idler in turn meshes with a gear wheel 21 rigidly secured to shaft 17. The shaft 18 may be driven through any suitable connections with a source of power.

As shown in Fig. 4, a sprocket wheel 22 is secured to shaft 18 and accommodates the chain 23 which fits over the sprocket wheel 24 secured to the shaft 25. As this shaft is driven from the power connected with the pulleys 8 shaft 18 will therefore be driven at the right proportion of speed. As indicated in Fig. 4, shaft 25 carries sprocket wheels 26 and 27, sprocket wheel 26 accommodating chain 28 while sprocket wheel 27 accommodates chain 29 fitting over the sprocket wheel 30. The sprocket wheel 30 is rigidly secured to shaft 31 which shaft has a second sprocket wheel 32 rigidly secured thereto and accommodates the chain 9 which chain also passes over a sprocket wheel 33 secured to shaft 7 on which the pulleys 8 are mounted. By this arrangement of drive the parts are driven in the right direction and at the right proportion of speed to secure the results desired.

By means of this mechanism it will be observed that as the sprocket wheels 19 and 21 rotate, bars 12 and 12' will reciprocate. These bars accommodate a number of rollers 34 and 35 respectively over which the cloth or other matter 36 passes as the machine operates. The shaft 7 is rigidly secured to the roller 4 which roller acts as a driving member or a driving drum and co-acts with the driving drums or rollers 36 and 37 rigidly

secured to the shafts 31 and 25 respectively. By this arrangement the cloth or other material in tank 1 is being driven from three points though it is evident that a greater or less number of driving rollers could be provided. The driving motion is continuous and acts during the reciprocation of the bars 12 and 12' so that there will be a continuous passage of the cloth through the machine and, consequently, a uniform treatment thereof. The reciprocation of rods 12 and 12' is preferably rather small and as an example, may be only four inches where the bars are four feet apart.

15 In order to compensate for the different positions of the rollers 34 and 35, a number of tension rollers are provided, namely, rollers 38, 39, 40 and 41 for tank 1. Ordinarily this number of tension rollers will be sufficient though a greater number may be used if desired and also if desired the tension rollers may be of the gravity type as shown in Fig. 1 of the drawing or may be positively driven either in the same manner as shown in my prior patent or in some other equally desirable way. The roller 37 has associated therewith a squeezing roller 43 which is mounted on shaft 45 which shaft is eccentrically mounted on suitable bearings 47 and said eccentric is provided with an arm 49 accommodating the weight 51 which may be adjusted along the arm for causing a greater or less pressure of the roller 43 against roller 37. A squeezing action of roller 43 is especially important in view of the fact that the cloth passes from tank 1 over into tank 2 which latter tank may in some circumstances contain a different liquid from that provided in tank 1.

40 When the parts are arranged as shown in Fig. 1 all that is necessary to do is to start the parts moving which will take place as soon as the pulleys 8 are rotated. The goods either as woven fabric in open width or as warp yarn in chain form will be fed from any suitable supply to roller 4 and thence will pass over the various tension rollers and also rollers 34 and 35 as well as the rollers 36 and 37. During the passage-way of the cloth through the tank it is subjected to the action of the liquid in the tank which may be dye, a scouring compound or other liquid for treating cloth.

By reason of the reciprocation of the bars 12 and 12' the cloth is moved flat-wise against the liquid whereby the liquid is forced in a certain sense to penetrate the cloth for dyeing and cleaning purposes or for some other desirable purpose.

55 60 Under some circumstances the movement of the rollers 34 and 35 with the bars 12 and 12' would produce an undesirable tension on the cloth passing through the machine but in order to provide a complete structure which will take care of all kinds

of fabric under all circumstances, there is provided a pair of rollers 52 and 53 between the runs of cloth beneath the respective rollers 35 as clearly shown in Fig. 1. These rollers are mounted upon suitable end bars 54 which end bars are connected to suitable shafts 55. Each of these shafts is provided with a sprocket wheel 56 for receiving the chain 57, which chain also passes over a sprocket wheel 58 connected with the idler 20, which idler acts as a driving member for the chain. As the chain 57 engages all of the gear wheels 56 connected to the respective shafts 55, all of the shafts will be rotated in unison and, consequently, the rollers 52 and 53 will be moved in a circle continuously as long as the machine is in operation and will assume the position shown in Fig. 1 when the position of the rollers 34 and 35 have a tendency to produce slackness in the various runs of fabric. As the rollers move they will tend to take up this supposed slackness and in order to allow such action, the chain 57 moves the various parts including the rollers 52 and 53 until said rollers are out of the way. By this mechanism a substantially even tension is provided on the fabric as it passes through the machine so that there will be no stretching or distortion of the fabric.

In exceptional cases when using the machine for scouring purposes, a brush could be arranged above one of the feed rollers, as for instance, roller 36 so that a thorough cleaning action will be produced. This brush could reciprocate, rotate or move in any desired manner.

What I claim is:

1. A vat for treating textile fabrics in open width with liquid consisting of a compartment, a frame structure arranged in said compartment with fabric carrying rollers, means for operating said frame to cause the fabric to engage the liquid flat-wise while in the substantially vertical position and means for feeding said fabric through said compartment.

2. A device for treating textile fabrics with liquid comprising a vat for containing the liquid, a pair of spaced reciprocating bars acting as a frame, rollers arranged on each of said bars adapted to receive the fabric to be treated and over which said fabric passes, means for feeding fabric through said vat over said rollers, means for reciprocating said bars, and means for moving said reciprocating bars simultaneously in opposite directions.

3. A machine for treating textile goods with liquid, comprising a compartment, means for guiding the goods into said compartment, a plurality of rollers arranged in said compartment acting as guides for said goods while in the compartment, means for simultaneously shifting the rollers, said

means shifting half the rollers in one direction and half the opposite direction and means for connecting said shifting means.

4. A device for treating fabrics in open width or warp yarns in chain form comprising a vat for containing a treating liquid, a pair of reciprocating spaced bars arranged in said vat, means for moving said bars simultaneously in opposite directions, a plurality of guide rollers arranged on each of said bars for guiding the goods to be treated through said vat, feeding means for feeding the cloth through the vat and a squeezing roller for squeezing the goods as they pass from the vat.

5. A device for treating textile fabrics comprising a tank for receiving a treating liquid, a pair of spaced reciprocating bars arranged in said tank, a plurality of rollers

arranged on each of said bars adapted to 20 guide the fabric as it passes through the vat, means for driving said fabric, means for maintaining a tension in said fabric as the bars reciprocate and move said driving rollers and driving means connected with said 25 bars for causing a reciprocation thereof.

6. A device for treating textile fabrics with liquid comprising a tank for receiving the treating liquid, reciprocating means in said tank for receiving the fabric so that the 30 fabric will extend substantially in a vertical position, means for moving said reciprocating means so that said fabric will be engaged substantially flat-wise, a liquid in said vat and driving means for moving the fabric 35 through the vat.

LOUIS CLARENBACH.
